UNITED STATES PATENT OFFICE

160,880

AUTOMOBILE BUMPER

Milo J. O'Leary, Rochester, Mich., assignor to
Chrysler Corporation, Highland Park, Mich., a
corporation of Delaware

Application August 13, 1949, Serial No. 4,462

Term of patent 7 years

(Cl. D14—6)

To all whom it may concern:

Be it known that I, Milo J. O'Leary, a citizen of the United States, residing in the city of Rochester, county of Oakland, and State of Michigan, have invented a new, original, and ornamental Design for an Automobile Bumper, in which the following is a specification, reference being had to the accompanying drawing, forming part thereof, in which:

Fig. 1 is a top plan view of a bumper incorporating my novel design;

Fig. 2 is a front elevation of the bumper;

Fig. 3 is an end elevation of the bumper; and

Fig. 4 is a vertical section taken on the line 4—4 of Fig. 2.

I claim:

The ornamental design for an automobile bumper substantially as shown.

MILO J. O'LEARY.
